Dallas, Tex., a corporation of Delaware
Filed June 13, 1966, Ser. No. 557,081
8 Claims. (Cl. 137—155)

This invention is concerned with a gas lift flow valve used in production of oil and gas from wells and is particularly concerned with a wireline retrievable flow valve of the pressure charged type with integral check valve which may be used in conventional offset mandrels now in use in the field.

It is the primary object of the invention to provide a pressure charged valve assembly in which the natural relationships between operating pressure, pressure dome volume, bellows size, bellows stroke, valve size, and operating tubing pressure may all be used for maximum operating characteristics and efficiency.

A problem has been caused in the gas lift industry by a universally used standard "side-pocket" or offset mandrel for wireline retrievable gas lift flow valves. The spacing of the sealing elements on the valve housing for functional engagement between the valve and the mandrel is fixed, and the length of the flow valves is determined by the necessary clearances for attachment of running and retrieving tools. Furthermore, the latch mechanism by which the flow valve is seated and retained in the mandrel is fixed by certain dimensional limitations.

In the present invention, there has been provided a valve with an enlarged pressure dome which is functionally equivalent to a much longer valve or one of much greater diameter than would be required in the absence of the above limitations, yet which will fit into and functionally operate in the offset mandrel now in the field.

The most important physical characteristics of a pressure operated flow valve for efficient use are: the volume of the pressure dome (excluding the volume which may or may not be filled with a non-compressible fluid for safety purposes), the effective area of the bellows, the stroke of the bellows necessary to obtain full opening of the valve element, and the area of the port through which fluid flow is controlled by the flow valve. A functional characteristic which is highly important is the use of an adequate check valve which will control back-flow of fluids through the valve under high pressure acidizing, treating, or hydrostatic pressure conditions and yet allow the true operating tubing pressure of the installation to be effective during the operating cycle on the area of the valve element equal to the area of the port through which the gas injected.

The above characteristics determine the four critical pressures required for efficient use of gas lift in secondary recovery. These four critical pressures are (1) the pressure of the compressible fluid in the pressure dome, (2) the maximum operating pressure desired, (3) the opening pressure of the flow valve (pressure required to "crack" the valve), and (4) the tubing pressure present and effective against the valve element over the area equal to the valve port at the time the valve is "cracked."

The opening pressure of the valve is determined by an equilibrium point at which time the dome pressure acting across the effective area of the bellows equals the sum of the casing pressure (actually the opening pressure), plus the tubing pressure acting across the area of the port.

This equilibrium point is also affected by the spring tension in the bellows, which is usually negligible but which can be easily corrected for. It should be obvious that when the flow valve is "cracked," the injection gas, being opposed by inertial load due to the liquid slug is

2

to be recovered from the well, rapidly approaches and becomes substantially equal to the casing pressure at the opening point.

The valve stroke is a design characteristic of the flow valve. It should definitely be long enough to completely open the valve port for injection of gas and yet should not be longer than this because of the induced flexure of the bellows, which will rapidly use up the fatigue life thereof and cause ultimate failure of the valve.

The volume of the pressure dome is also a design feature of the flow valve inasmuch as the increase in pressure therein due to the stroke of the valve and its compressive action on the gas in the dome results in a maximum dome pressure which should be smaller than the opening pressure of the valve. That is to say, the maximum pressure in the pressure dome when the valve is full open should be less than the opening pressure of the valve.

The reason for the foregoing conclusion is as follows: from an ideal and efficiency standpoint, the opening pressure of the valve and the closing pressure of the valve should represent a pressure drop over the annulus volume containing the gas to be injected sufficient to lift the predetermined slug of liquid from the hole. Highest efficiency from the installation will be obtained when this condition is most nearly present. The stroke of the valve is and should be designed into the valve with certain mechanical limitations. However, if inadequate volume is designed into the pressure dome, the maximum dome pressure will result before the full stroke of the valve has been obtained and inefficient injection will follow resulting from premature reverse stroke of the valve toward the closed position, causing throttling which further decreases efficiency. If the designed pressure dome volume is such that the maximum pressure in the dome results concurrently with the maximum stroke of the valve, full opening will be instantaneously achieved, but the premature reverse stroke of the valve toward closed position will immediately result from a drop in pressure in the annulus before the valve has remained open for the desired time and throttling will result with loss of efficiency.

Therefore, a dome volume should be provided which will result in a full stroke of the valve but having a maximum dome pressure considerably less than the opening pressure of the valve so that the valve will be allowed to remain full open through a substantial and calculable portion of the range of the annulus pressure drop.

The above comments apply to intermittent gas lift flow wherein full valve opening is required. However, in continuous gas lift flow, the operating pressure range of the valve is ideally in the throttling range and it should be obvious that the limitations of the pressure dome volume should be such that it can be designed for the ideal situation in either intermittent or continuous flow. This has been an ever present problem in the gas lift industry, the solution to which has been approached in valves not restricted in their design parameters by the universally used side-pocket mandrels as mentioned above.

Now, this present invention allows a solution of this problem even under the restricted parameters described in connection with valves used in side pocket mandrels.

Of further importance in the design of an efficient gas lift valve and gas lift installation is the check valve assembly. The check valve must efficiently control back flow through the flow valve under conditions of acidizing, fracturing, treating, etc.; and in the absence of any other problems, a straight spring-loaded check valve would be suitable. However, since the tubing pressure effective over the area of the port on the valve ball of the flow valve is a vital factor in the design of the flow valve, especially

as port sizes increase for more rapid and efficient injection of gas, and since the nature of gas lift assumes that the closing pressure effective against the port area of the flow valve will be somewhat lower than the opening pressure effective against the port area due to the fill in of fluid to be ejected, a spring-loaded check valve usually prohibits the true reflection of the tubing pressure on the valve stem and thereby prohibits the effective use of the tubing pressure in design calculations for flow valves or installations.

A straight velocity check valve would be effective in allowing the true tubing pressure to be reflected on the valve stem, but is highly inefficient in controlling the backflow under the many conditions of velocity to which said backflow is subjected.

In the present invention, there is disclosed a check valve which is spring loaded to a position of restricted flow which will allow the true tubing pressure to be reflected on the valve stem under conditions of no-flow, but will immediately react and be highly effective in controlling backflow under treating conditions.

A suitable embodiment of the invention is shown in the attached drawing, wherein,

FIGURES 1 and 1-A are a quarter-section elevational view of a preferred embodiment of the gas lift valve herein described showing it mounted in a conventional side pocket mandrel.

Numerical references are employed to designate the various parts shown in the drawing.

DESCRIPTION

Referring to FIGURE 1, there is a latch nose 1, which has an upwardly and inwardly tapered contour 2 thereon which is functionally adapted to facilitate attachment of the flow valve to a running tool and to guide a retrieving tool onto and about the flow valve. There is a downwardly facing shoulder 3 and an undercut section 4. The undercut section and the downwardly facing shoulder 3 are adapted to hold the flow valve in the running tool. A suitable form of running tool is described under the title KB-2 running tool on p. 111 of the 1964-65 Edition of the Composite Catalog of Oil Field Equipment and Services.

The mating threads 5 rigidly attach the latch nose 1 to a pressure dome 6 having a portion 7 about which a latch sleeve 8 is arranged. The companion threads 9 connect a latch seal retainer 10 to pressure dome 6. The latch seal retainer 10 has an upwardly extending portion 11 and an upwardly facing shoulder 12. The upwardly extending portion 11 is arranged for slidable engagement with the latch sleeve 8 and the upwardly facing shoulder 12 is arranged to limit the downward movement of a downwardly extending enlarged portion 13 of the latch sleeve 8. A latch dog 14 is slidably arranged about portion 13 and is seated on the upwardly facing shoulder 12. There is an undercut portion 15 in the outer surface of the latch sleeve 8 and a downwardly facing shoulder 16 is formed thereabout.

The latch spring 17 abuts the downwardly facing shoulder 16 of the latch sleeve 8 at the upper end and abuts the upper surface 18 of the latch dog 14 at the lower end thereof. There is an upwardly facing tapered shoulder 19 on the latch sleeve 8. The latch sleeve 8 is disengagedly attached to the pressure dome 6 by means of shear screws 20. There is also a downwardly facing tapered surface 21 on the latch dog 14.

The function of the several latch elements heretofore described will be adequately explained hereinafter in connection with the description of the operation of the valve and latching mechanism.

The seal retainer O-ring 22 is arranged for sealing engagement between the interior surface of the latch seal retainer 10 and the outer surface of the pressure dome 6.

The upper seal assembly 23 is retained between the lower end 24 of the latch seal retainer 10 and an upwardly

facing shoulder 25 formed about the lower portion of the pressure dome 6. The upper seal assembly 23 is adapted for sealing engagement between the pressure dome 6 and the sealing bore 92 provided in the side-pocket receiver 91 of the mandrel 86.

It will be understood that the novel construction and function of the valve herein described is not limited to nor dependent upon the particular functions and arrangement of the above described latch parts. Other latch mechanisms consistent with particular side-pocket mandrel configurations could be used.

The enlarged portion 26 of the pressure dome 6 has a counterbore 27 arranged therein for engagement about a safety valve ring 28, said enlarged portion 26 and the safety valve ring 28 being secured together as by brazing or other pressure type attachment.

There is a relatively long and cylindrical counterbore 29 in the pressure dome 6 terminating in a smaller bore 30 in which is mounted, as by threads 31a, a valve core 31 and is closed by a sealing cap 32 by the mating threads 33. The valve core 31 may be of the type having a spring urged check valve stem therein which may be pushed down to open the valve for filling.

When the counterbore 29 has been charged to a predetermined pressure by a compressible fluid through valve 31 the sealing cap 32 is drawn downwardly by the mating threads 33 to compress a sealing gasket 34 to retain said predetermined pressure therein.

The safety valve ring 28 has a safety valve passage 35 therethrough adapted to receive in slidable engagement the upper portion 40 of a bellows core 37. The bellows core 37 has an upwardly facing tapered surface 38 adapted to engage the lower end of the safety bore passage 35 in pressure tight relationship when the valve has stroked to its upward limits. There is a safety stop pin 39 secured to the upwardly extending portion 40 of the bellows head 37 which is arranged to stop the motion of the bellows core 37 when it has stroked into its maximum position in the downward direction.

A flexible metallic bellows 41 is brazed to the safety valve ring 28 at its lower extremity 42 and is similarly brazed to the bellows core at the lower end as at 43.

The above described structure forms a closed and pressure tight pressure chamber which includes the dome portion 44 and bellows 41 which is filled with a compressible fluid such as nitrogen, except for the lower portion defined by the interior of the bellows 41, the counterbore 36, and the safety valve passage 35. The excepted areas are usually and preferably filled with a non-compressible safety liquid 44a such as silicones in order that when conical surface 38 engages and closes passage 35 the non-compressible liquid will be trapped in the bellows 41 to protect it against damage by extreme exterior pressures.

The general function of the above described pressure chamber is similar to the conventional pressure operated flow valve, except that one of the improvements described by this invention is the dual usage of the dome portion 44 as a functional gas lift valve part and is incorporated in the means for running, latching and retrieving the gas lift valve from a retrievable gas lift valve mandrel.

The bellows core 37 is attached by the mating threads 45 to a valve stem 46. The effective length of the valve stem 46 may be adjusted by the placement of one or more shims 47 between the valve stem and the core 47.

The counterbore 48 in the lower end of the valve stem 46 has threads 49 therein by which a replaceable valve stem 50 may be attached thereto. The lower end of the replaceable valve stem 50 has a valve head 51 thereon, which may be made of hard material such as tungsten carbide.

The bellows housing 52 is attached to the safety valve ring 28 at the mating threads 53 and depends therefrom to enclose the bellows assembly and permanent and replaceable valve stems.

Ports 54 define a passageway for the injected gas the flow of which is controlled by the valve head 51. The mating threads 56 provide for rigid attachment of a latch sleeve housing 57 to the housing 52 a passageway 58 therethrough and an inner upwardly facing shoulder 59 therein. The upwardly facing shoulder 59 in the latch seal housing 57 and the downwardly facing shoulder 55 in the bellows housing 52 retain in place a valve seat body 60. The valve seat O-ring 61 establishes a pressure tight seal between said valve seat body 60 and the latch seal housing 57. A valve seat 62 is attached in the upper end of the bore 63 in the valve seat body 60, said valve seat 62 being preferably made of tungsten carbide or similar materials.

The latch seal housing 57 has an undercut portion 64 providing downwardly facing shoulder 65, said undercut portion and downwardly facing shoulder defining the position of a lower seal assembly 66. The lower seal assembly 66 is held in place by the upper end 67 of the check valve seat 68, which is attached to the latch sleeve housing 57 at the mating threads 69.

The lower seal assembly 66 engages the sealing bore 93 in the receptacle 91 of side-pocket gas lift mandrel 86 and is in spaced relationship to the upper seal assembly 23. Between the seal assemblies 23 and 66 there is an enlarged bore 98 in the receptacle 91 with which ports 54 and 90 communicate to provide continuous passageway for gas from the exterior of the mandrel 86 to the interior of the flow valve.

The check valve seat 68 has an internal bore 70 therethrough which is a continuation of the passageway 58 in the latch seal housing 57 and provides a seating face 71 for contact with a check valve head 72 and further provides a counterbore 73 the function of which will be hereinafter described.

The check valve head 72 has a check valve stabilizer body 74 brazed or otherwise rigidly affixed thereto, which has an internal bore 75 and ports 76 through the wall defining passageways for the injected gas either from above or below.

The check valve stabilizer 74 also has a downwardly facing shoulder 77 thereabout adapted for contact with the upper end of the check valve spring 78. The lower end of the check valve spring 78 is abutted against an upwardly facing shoulder 79 in the check valve housing 80. The check valve housing 80 encloses the check valve ball 72 and the stabilizer 74 and is attached to the check valve seat 68 at the mating threads 81 therebetween. The check valve housing 80 has an inwardly extending portion 83 and a downwardly and inwardly facing contour 84 thereon. The contour 84 guides the flow valve into position in the receptacle 91 of side-pocket mandrel 86. The check valve housing 80 has ports 85 extending through the lower end thereof defining passageways for the injected gas either from above or below.

The mandrel 86 has threads 87 and 88 in the upper and lower ends which are arranged for attachment in a tubing string, the passages at each end being concentric with the tubing string.

The mandrel is provided with an offset portion 89 in which the receptacle 91 is mounted. The receptacle 91 has an open lower end 94 communicating with the tubing string.

A semi-circular shoulder 95 having tapered guide surfaces 96 and 97 on the upper and lower sides thereof is provided on the inner side of the offset portion 89 of the mandrel. The shoulder 95 is located directly above and concentric with the bore of the receptacle 91.

OPERATION

When the flow valve representing the present invention is desired to be run into the hole, it is attached to a running tool and kickover tool such as that described on pp. 1111 and 1112 of the 1964-65 edition of the Composite Catalog of Oil Field Equipment and Services. The

flow valve is retained in the running tool by tangential shear pins (not shown) which pass through the undercut portion 4 of the latch nose 1 and bear against the downwardly facing shoulder 3 of the latch nose. Downward pressure is exerted on the flow valve by the lower end of skirt of the running tool landing against the upwardly facing shoulder 19 of the latch sleeve 8. The kick-over tool is manipulated as described on the above pages of the Composite Catalog and the flow valve is deflected laterally into the receptacle 91 of the mandrel by the tapered profile 84 of the check valve housing 80, contacting the upper end of the bore of the receptacle.

As the flow valve is inserted into the receptacle 91 the latch ring 14 will contact shoulder 95 and further movement downward of the valve will cause latch ring 14 to rise above the enlarged downward depending portion 13 of the latch sleeve 8, simultaneously compressing the latch spring 17; but when the latch ring 14 moves adjacent the reduced portion 15 of latch sleeve 8, the latch dog 14 is free to float eccentrically of the portion 15 and thereby be in position to move laterally sufficient to pass the shoulder 95. The downward motion of the valve is stopped when the downwardly facing shoulder 10a of the latch seal retainer 10 comes in contact with the upper end of the receptacle 91, and the compressed latch spring 7 is free to force the latch dog 14 back into position around the enlarged downwardly depending portion 13 of the latch sleeve 8. In this position, the latch dog 14 now being concentric with the valve receptacle cannot move laterally to pass above the shoulder 95 and the valve will therefore be latched into the receptacle 91.

The running tool and kick-over tool combination is then jarred free from the flow valve by shearing the tangential shear pins (not shown) in abutment with the shoulder 3 of the latch nose 1 and the tools are removed from the hole leaving the valve in place as shown in FIGS. I and I-A.

If and when the valve is to be retrieved from the mandrel, a combination of the kick-off tool mentioned above and a pulling tool, generally described on p. 1110 of the 1964-65 edition of the Composite Catalog Oil Field Equipment and Services is used. The tapered surfaces 2 of the latch nose 1 guides the pulling tool over and around the flow valve. The pulling tool has a collet, or latch dog arrangement which fits into the undercut 8b of the latch sleeve 8 and pulls on the flow valve through the shoulder 8a of the latch sleeve 8.

Inasmuch as the valve assembly is held rigidly in the receptacle 91 by means of the latch dog 14 in contact with the shoulder 95, upward pull, usually applied by wireline jars, will result in shearing the shear screws 20 enabling the enlarged portion 13 of the latch sleeve 8 to be pulled upwardly from within the latch dog 14. When this occurs, the latch dog 14 is free to float eccentrically within and move laterally to permit it to pass above the shoulder 95, and the combination of the kick-over tool, pulling tool and flow valve may be retrieved from the tubing.

The outside of the flow valve intermediate the upper and lower seal assemblies 23 and 66 is subjected to the annulus pressure between the casing and tubing through ports 90. This annulus or operating pressure is communicated into the valve through the ports 54 and is effective on the pressure reactive bellows 41 over an area determined by the difference between the effective area of the bellows and the area of the valve 51 co-acting with the valve seat 62. The action of the operating pressure on the above defined areas creates a force tending to move or raise the valve 51 from the valve seat 62, and this upwardly acting force is increased by the pressure from the tubing string communicating through the ports 85, the counterbore 75, the ports 76, and around the relatively restricted passageway defined by the check valve 72 and the counterbore 73 of the check valve seat 68 and thence upwardly through the passageways 70, 58 and 63 to the valve head

51 over an area determined by the diameter of the valve seat 62. When the sum of the above two forces generated by the respective pressures equals the downward force generated by the gas pressure in the counterbore 29 of the pressure dome 6 (which communicates to the interior of the bellows 41 through the bore 35 of the safety valve ring 28 and is thus acting on the effective area of the bellows 41), then cracking or opening of the valve is impending. When the valve is cracked or slightly opened, as explained hereinabove, the annulus or operating pressure will instantaneously become effective over the entire effective area of the bellows 41 and the valve head 51 will be further raised to completely open the valve. This rise of the valve head 51 is limited by contact of the tapered surface 38 with the safety valve ring 28 and when such contact is made, the non-compressible safety fluid 44a will be trapped in the bellows to protect the relatively fragile bellows from damage due to excessive increases in pressure.

Assuming that the pressure chamber 44 has been charged with a compressible fluid to a predetermined opening pressure (pressure at which cracking of the valve is impending) the mechanical stroke of the bellows causes a volumetric change in the pressure chamber 44 effective over its effective area and will increase the charged pressure of the dome portion thereof to an extent dependent upon the volumetric capacity of the dome portion 6. This will be the maximum pressure to which the compressible gas in the dome portion can be subjected.

It is important that the volumetric capacity of the dome portion 6 be large enough for the pressure increase induced by the bellows stroke to result in a maximum dome pressure substantially less than the operating pressure of the valve. If this does not occur, the valve would reverse its stroke immediately upon a draw down in the operating pressure due to gas injection into the tubing string, but conversely if there is a substantial difference between the maximum dome pressure and the operating pressure, injection can occur over a substantial range of the total pressure drop in the casing annulus before such a reversal of stroke occurs and the valve moves toward a throttling position and eventually to a closed position.

The tubing pressure opposite a particular gas lift valve goes through a wide variation during the cycle of an intermittent gas lift installation. At the time the valve is designed to open, there is an appreciable tubing pressure present due to the accumulation of well fluids in the tubing above the flow valve which is subject to education in each cycle. As explained above, when the valve is opened and injection of annulus gas is begun, there is an immediate upsurge in the tubing pressure due to the inertia of the fluid column to be moved to a degree that approaches, if not equals, the operating pressure of the valve. After the slug has begun movement toward the surface and injection continues, there will be present a slowly decreasing tubing pressure with values parallel to the drawdown of the casing annulus pressure as the gas is injected under the slug.

For most efficient operation, the installation should be designed for the flow valve to close slightly before the slug starts emerging from the tubing at the surface and when this occurs, there will be a more rapid decline in the tubing pressure due to the expansion of the gas present and limited only by the overall operating pressure of the system, chiefly due to back pressure at the wellhead. Immediately thereafter, there will be a relatively rapid increase in tubing pressure due to the accumulation at the valve of that portion of the original slug termed fall-back, which reaccumulates at the valve and immediately above. The pressure due to fall-back (plus normal system pressure) is repeated during each cycle. The tubing pressure opposite the valve will then begin a relatively slow increase, which is a measure of the rate and amount of well fluids being forced into an ejectable position by the well.

When the tubing pressure reaches a value representing the desired slug, control equipment at the wellhead actuates the installation into another cycle by either pressure or time control.

Automatic cycling may be obtained if the tubing pressure in passageway 63, effective on the valve head 51 over the area of the valve seat 62, is the true tubing pressure, by pressure manipulation in the annulus simultaneously with the variations of the tubing pressure after the valve is closed. This follows from the fact that although the casing pressure has been built up to the opening pressure of the valve, the opening of the valve will be prohibited by the pressure in the dome acting downwardly over the entire effective area of the bellows, and will not be overcome until the tubing pressure effective on the area of the valve seat 62 reaches the desired point.

The above conditions could be met with a straight velocity check valve in the gas lift valve, but such a check valve would not be susceptible to backflow of small degree very often present in acidizing and treating operations. Neither would it be effective under conditions of gas input failure wherein the slow fill-in from the well bore would create an abnormal back pressure, but at such a rate that considerable and substantial fluid could be lost into the annulus.

In contrast, the check valve assembly, described above, with the check valve head 72 biased into the counterbore 73 with relatively small clearance therebetween, would be highly effective under conditions of slow backfill and slow back pressure increases, and would be effectively swept into position against the check valve seat 71 to prohibit such backflow. Similarly, the clearance, though small, between the check valve 72 and the counterbore 73 would be sufficient for communication of the tubing pressure and would definitely give assurance that the true tubing pressure opposite the valve is present in the passageway 63 and effective over the area of the valve seat 62.

The true opening relationship between the above pressures is obtained as follows: Under conditions of no flow, the check valve head 72 is urged upwardly into the counterbore 73 of the check valve seat 68 by the check valve springs 78, but does not come into contact with the check valve seat 71. Furthermore, there is a relatively small clearance between the diameter of the check valve head 72 and the counterbore 73, but there is no restriction of the tubing pressure communicating through the ports 85 and upwardly to the passageway 63 and exerting its true value on the bottom of the valve 51 over the entire area of the valve seat 62.

However, when the valve 51 is open and gas is being injected into the tubing, the velocity of flow will depress the check valve 72 by compressing the spring 78, moving valve head 72 out of bore 73, and adequate passageway 55 will be obtained for efficient flow for the injection cycle. Similarly, back-flow induced by sudden fluid surges or by the application of acidizing or treatment pressure, being restricted by the relatively small clearance between the check valve ball and the counterbore will sweep the check valve head 72 upwardly into engagement with the check valve seat 71 and further flow will be effectively prohibited.

It may be seen then, that the proper construction of the check valve assembly will allow the calculable use of the true tubing pressure which, properly used in relationship to the valve seat area and the operating pressure in the annulus, will determine an efficient valve opening limited by the structure of the bellows head 37 and the safety valve seat, which allows proper bellows protection against pressure overrides, allows an optimum volume of compressible gas to be designed into the valve for best and efficient use of the valve in controlling the injection of gas from the annulus to the tubing, all of which is obtained within the structural limitations imposed by universally used offset mandrel equipment. This

universally used mandrel equipment was designed from the standpoint of efficiency in placing and removing a gas lift valve rather than from the standpoint of efficiency in the gas lift valve itself and the valve assembly herein described adapts the valve for most efficient use therewith.

Having described our invention we claim:

1. In a flow valve, a pressure chamber, a sealed bellows diaphragm suspended below the pressure chamber and being in fluid communication therewith, said pressure chamber and bellows diaphragm being charged at a predetermined pressure; a valve stem and head suspended below the bellows diaphragm; a valve seat housing having a passage therethrough with a valve seat thereabout arranged to receive the valve head; a bellows housing about the bellows diaphragm between the pressure chamber and the seat housing; a port through the wall of the bellows housing communicating with the valve head and seat; and a latch assembly surrounding the pressure chamber arranged to disengagably latch the flow valve in a mandrel receptacle.

2. The combination called for in claim 1 with the addition of a backflow check valve suspended below the valve seat housing having a passage therethrough communicating with passage through the valve seat housing.

3. The combination called for in claim 2 wherein the check valve includes a spring urged hollow body having a valve head thereon; ports through the wall of the hollow body below the head; the passage through the check valve including a counterbore with a seat at the upper end thereof, spring means urging the head toward the seat but not sufficient to cause it to contact said seat; and an annular space between the counterbore and the valve head.

4. In combination with a valve receiving mandrel having a valve receptacle therein of a gas lift flow valve latched in the receptacle, said flow valve including a pressure chamber with a bellows diaphragm suspended thereto in communication therewith, a valve seat and passage

therethrough, a valve head carried by the diaphragm arranged to control flow through the passage; and means attached about the pressure chamber to latch the flow valve in the receptacle.

5. The combination called for in claim 4 with the addition of a back flow check valve attached below the flow valve, said check valve including a seat, a valve head and spring means urging the valve toward the seat but not of sufficient strength to urge the valve against the seat; there being a bore extending below the seat, the said valve being urged into the bore by the spring means; and there being an annular passage between the valve and the bore.

10 6. The combination called for in claim 4 wherein the portion of the pressure chamber with latch means thereabout extends above the receptacle.

7. In a gas lift flow valve; a pressure chamber; a bellows diaphragm suspended below the pressure chamber and being in communication therewith; a valve seat and passage therebelow; a valve head suspended to the bellows diaphragm arranged to control flow through the passage; and latch means disposed about the pressure chamber for latching the valve in the receptacle of a mandrel.

20 8. The combination called for in claim 7 with the addition of a wire line tool engaging fitting on the upper end of the valve above the latching means.
